(57) **CLAIM**

The ornamental design for gas soldering iron, as shown and described.

DESCRIPTION

FIG. 1 is a perspective view of a gas soldering iron showing the design;

FIG. 2 is a front side view thereof;

FIG. 3 is a rear side view thereof;

FIG. 4 is a left side view thereof;

FIG. 5 is a right side view thereof;

FIG. 6 is a top elevation view thereof; and,

FIG. 7 is a bottom elevation view thereof.

The broken lines are included for the purpose of illustrating portions of the gas soldering iron that form no part of the claimed design.
